UNITED STATES PATENT OFFICE.

ROBERT L. SHORT, OF FOSTORIA, OHIO, ASSIGNOR, BY MESNE ASSIGNMENTS, TO HARVEY S. LINHART AND CURTIS C. LINHART.

HOT-AIR HEATER.

933,128.

Specification of Letters Patent. Patented Sept. 7, 1909.

Application filed November 15, 1906. Serial No. 343,582.

To all whom it may concern:

Be it known that I, ROBERT L. SHORT, a citizen of the United States, residing at Fostoria, in the county of Seneca and State of Ohio, have invented a certain new and useful Improvement in Hot-Air Heaters, of which the following is a full, clear, and exact description, reference being had to the accompanying drawings.

10 This invention relates to air heating systems, and it has particular reference to a heater that is depressed below the floor level, the upper surface of the heater being supported upon the floor and consisting of an open grate structure similar to that employed in the ordinary hot air register.

15 The heater is intended especially for use with gas, and it has the advantages of economy in the use of fuel, of great heating capacity, and of use in such position that the heater occupies practically no space in the rooms where used.

20 In the drawings accompanying this application, Figure 1 is a vertical central longitudinal section through the heater showing the arrangement of the parts therein. Fig. 2 is a transverse horizontal section taken substantially on the line 2--2 of Fig. 1.

25 In the ordinary hot air systems where a large furnace is employed, with hot air pipes leading to registers throughout the building, there is necessarily a great loss of heat incident to the transmission of the hot air from the furnace to the various registers and in the incidental heating of the said conducting pipes. Furthermore, in the use of such furnaces when but little heat is required, there is always a considerable loss due to the employment of a large furnace. In my 30 heater, this loss is almost entirely avoided for the reason that there are no conducting pipes to be heated, and the heaters being located immediately beneath the floors of the rooms to be heated, there can be no loss due 35 to any of the above mentioned causes. My system of heating, therefore, has the advantage of locating the heat at the various points needed, the heating devices so located being under absolute control from the room.

40 to be heated, whereby great convenience in control of the heating devices is secured.

45 Taking up the drawings for a more detailed description, 1 represents the floor of a room to be heated, in which floor an opening is cut similar to those now formed for the common hot-air register. Supported upon the edges of this opening is the outside casing 2 of my improved heater, said casing being preferably square in horizontal section, although this is not a necessary form. 50 This outside casing has a horizontal flange 3 at its upper end, which flange rests upon the floor and supports the heater. The casing is continuous across its bottom 4, with the exception of a small opening at the center through which the fuel pipe 5 is extended. At one side and near the bottom of the casing, I provide a door 6 through which access may be had to the burner for lighting and adjusting the same. The upper end of 55 the casing 2 is open, except for a grated cover 7, similar to the cover for the ordinary hot-air register, said cover being provided on its lower side with a flange 8 which extends just inside the upper end of the casing 60 2, said flange not only holding the cover in place, but also strengthening the upper end of the casing.

65 Secured to the bottom of the casing, near each of the sides of the latter, are brackets 9, said brackets extending upwardly and thence inwardly toward the center of the casing. In their horizontal portion these brackets are provided with openings 10 for the passage of the air, as will be herein-after described. Supported upon said horizontal portions of the brackets is the interior heating drum 11, said drum being completely closed except at the center of its lower end where an opening 12 is provided. Within 70 the interior of the drum 11, and supported from the sides thereof by brackets 13 is a funnel-shaped member 14, the lower portion or apex of said member being directly over the center of the opening 12. Directly below 75 the apex of the member 14 is the burner 15. As appears from Fig. 1, the flame, covering the upper surface of the burner, impinges

against the lower surface of the funnel-shaped member 14, which spreads the flame outward and causes the heat to be directed against the outer surface of the heating drum 11, thereby heating said drum to a very high temperature.

While the amount of fuel consumed may be regulated in the burner, I provide in the fuel pipe 5, a valve 28, by means of 10 which the amount of fuel may be controlled or may be entirely cut off. To said valve, which may be of any suitable form, I attach a crank lever 29, to the free end of which I secure a chain or other flexible connection 15 30, said chain passing upwardly through the floor 1, within reach of the operator, who, by lifting upon said chain, may open the valve to any desired extent. For automatically closing the valve, I hang upon the free 20 end of the crank lever 29, a weight 31, which is sufficient to rock the valve and close the same when the chain 30 is loosened.

In order that the burner may be always in condition for use, I provide the same 25 with a pilot light, the necessary fuel for the same being supplied through a small pipe 32, that extends from the fuel pipe 5, at a point in advance of the valve 28. By thus arranging the pipe 32, fuel is supplied for 30 the pilot light irrespective of the condition of the valve 28. In order to cut off the supply fuel for the pilot light, I provide the pipe 32 with a valve 33.

Surrounding the heating drum 11, and 35 resting upon the brackets 9 above the opening 10 in the latter, is a cylinder being of somewhat larger diameter than the drum so as to afford a circumferential passage for the heated air. This passage is divided by 40 partition plates 35 into a plurality of vertically disposed flues 26, said flues extending from the space below the brackets 9 to the upper end of the heating drum 11. Also surrounding the cylinder 34, and resting 45 upon the brackets 9, is an open ended drum 37, said drum being constructed at its upper end, as shown at 38, so as to deflect the heated air inwardly away from the floor 1. The drum 37 is spaced from the cylinder 34 50 so as to afford a circumferential passage 39 for the heated air.

In order to prevent the products of combustion from passing into the room, I provide my heater with a pipe 40, said pipe being conducted through the casing and the various heating drums at a point somewhat above the funnel-shaped member 14, the inner end of said pipe being bent downwardly so that its open end is above the center of 60 said member 14, and almost on a level with the upper edges thereof. This pipe will of course be carried to a chimney so that the gases will be safely conducted from the heater.

From the above description, it will be understood that in the operation of the heater the hot air will ascend through the flues 36 and the space 39, displacing the air below the heating drum, and the cold air will pass downwardly inside of the casing 70 2 and outside of the drum 37, as indicated by the arrows in Fig. 1. The cylinder 34, with the partitions or vanes 35, form a very extended heating surface for the air passing about the same. By turning in the upper 75 end of the drum 37, as shown, the heated air is diverted from the edges of the plate 7, and the cold air coming down through the plate about its edges, keeps the heater always cold near the floor, thereby avoiding 80 all danger of overheating.

I claim:

1. The combination, with a floor, of a hot-air heater having a drum, means for heating said drum, a second drum surrounding the first mentioned drum, and spaced therefrom, a third drum surrounding both drums and constricted at its upper end, and means for causing the cold air to pass downwardly outside the third drum, whereby the 90 heated air passes upwardly between said drums and is directed away from the floor.

2. The combination, with a floor, of a hot air heater having a drum that is closed at its upper end, a cylinder surrounding said 95 drum and spaced therefrom, vanes dividing the space between the drum and cylinder into a plurality of flues; thereby affording an extended heating surface, a second drum surrounding and spaced from said cylinder, 100 said second drum being constricted at its upper end for diverting the heated air from the floor, means for heating the first mentioned drum, and means for supporting said drums, cylinder and heating means from the 105 floor of the room to be heated.

3. In a hot air heater, a casing, a drum supported within the said casing in such position as to afford a passage for air beneath the drum, said drum being closed at its upper end and having an opening in its lower end, a burner so located with respect to the said opening in the drum as to cause the flame to pass within the drum, a device mounted within the drum above the heater 115 for spreading the flame toward the sides of the drum, a pipe leading into said drum above said spreading device for conducting the products of combustion from the heater, and an open-ended drum surrounding the 120 first mentioned drum and spaced therefrom, said open-ended drum being constricted at its upper end, the space between the drums affording a passage for hot air and the space between the open-ended drum and the casing affording a passage for cold air.

4. In a hot air heater, a casing, a drum supported within the said casing in such po-

sition as to afford a passage for air beneath the drum; said drum being closed at its upper end and having an opening in its lower end, a burner so located with respect to the 5 said opening in the drum as to cause the flame to pass within the drum, a funnel-shaped member mounted within the drum above the burner for spreading the flame toward the sides of the drum, a pipe leading 10 into said drum above said spreading member for conducting the products of combustion from the heater, and an open-ended drum surrounding the first mentioned drum and spaced therefrom, said open-ended drum being constricted at its upper end, the space 15 between the drums affording a passage for hot air and the space between the open-ended drum and the casing affording a passage for cold air.

20 5. In a hot air heater, a casing that is supported from the floor of the room to be heated, said casing being closed at its lower end, brackets secured to the lower end of the casing within the same, a heating drum 25 mounted upon said brackets, a burner for heating said drum, and an open-ended drum also supported upon said brackets, said open-ended drum surrounding and being spaced from the heating drum, for the purpose 30 specified.

6. In a hot air heater, a casing that is supported from the floor of the room to be heated, said casing being closed at its lower end, brackets secured to the lower end of the 35 casing within the same, a heating drum mounted upon said brackets, a burner for heating said drum, and an open-ended drum also supported upon said brackets, said open-ended drum surrounding and being 40 spaced from the heating drum, and said open-ended drum being constricted at its upper end, for the purpose specified.

7. In a hot air heater, a drum that is closed 45 at its upper end, said drum having an opening in its lower end, means for supporting said drum from the floor of the room to be heated, a burner below the opening in the said drum, so that the flame of the burner will pass into the drum, a funnel-shaped 50 spreading member carried by the drum above the burner, a pipe leading into the drum above the spreading member for conducting the products of combustion from the heater, and means for diverting the heated air away 55 from the floor.

8. In a hot air heater, a casing that is supported below the floor of the room to be heated, brackets within said casing, a heating drum supported upon said brackets, said 60 heating drum being centrally arranged within the casing and having its upper end closed, a cylinder surrounding said drum and spaced therefrom, vanes connecting the cylinder and drum and dividing the space

therebetween into a plurality of flues, an open-ended drum also supported upon said brackets and surrounding said cylinder so as to afford a circumferential space therebetween, a funnel-shaped spreading device within the first mentioned drum, said drum having an opening below said spreading device, a burner below said opening, and a pipe leading into the said first mentioned drum for conducting the products of combustion from the heater. 75

9. In a hot air heater, a casing that is supported below the floor of the room to be heated, brackets within said casing, a heating drum supported upon said brackets, said heating drum being centrally arranged within the casing, and having its upper end closed, a cylinder surrounding said drum and spaced therefrom, vanes connecting the cylinder and drum and dividing the space therebetween into a plurality of flues, an open-ended drum also supported upon said brackets and surrounding said cylinder so as to afford a circumferential space therebetween, the upper end of said open-ended cylinder being constricted for the purpose 90 specified, a funnel-shaped spreading device within the first mentioned drum, said drum having an opening below said spreading device, a burner below said opening, and a pipe leading into the said first mentioned drum 95 above the spreading device for conducting the products of combustion from the heater.

10. In a floor heater adapted to be supported from a floor with its upper end substantially flush with the floor, the combination of a casing depending from the floor and closed at its lower end, an open-ended drum supported within said casing and leaving an air space between it and the casing, the upper end of said drum being constricted, an inner drum within the drum first mentioned, an air passageway being formed between the two drums, and a burner within the inner drum. 100

11. In a floor heater, the combination of a casing adapted to depend from the floor of the room to be heated, said casing having a closed lower end, brackets near the lower end of said casing, two concentric drums supported on said brackets, means for heating the innermost drum, whereby the air may pass downward between the casing and outer drum and upward between said drum and the innermost drum, said innermost drum having its upper end closed, a burner discharging products of combustion into said innermost drum, and a pipe for conducting away such products of combustion. 110

12. In a floor heater, the combination of a casing adapted to depend from the floor and having a closed lower end, a drum within the casing supported above the bottom thereof and open at its upper end, a drum within 115 120 125

the open-ended drum and closed at its upper end, whereby an air passageway is provided downward from the room between the casing and outermost drum and upward between the two drums, the outermost drum being constricted at its upper end to direct the air across the upper end of the innermost drum, a burner adapted to discharge the products of combustion into the innermost drum, there being a pipe leading from

the innermost drum through the outermost drum and casing for such products of combustion.

In testimony whereof, I hereunto affix my signature in the presence of two witnesses. 15

ROBERT L. SHORT.
